WO 2012027403 A1 3/2012
WO 2015081404 A1 6/2015*Primary Examiner* — David G Muller*Assistant Examiner* — Nathan M Johnston(74) *Attorney, Agent, or Firm* — Andrus Intellectual Property Law, LLP(57) **CLAIM**

The ornamental design for a paper towel roll core, as shown and described.

DESCRIPTION

FIG. 1 is a left perspective view of a paper towel roll core according to my new and ornamental design;

FIG. 2 is a right perspective view thereof;

FIG. 3 is a front elevation view thereof, wherein the back elevation, top plan, and bottom plan views are identical to the front elevation view;

FIG. 4 is a right side elevation view thereof;

FIG. 5 is a left side elevation view thereof;

FIG. 6 is a left perspective exploded view thereof;

FIG. 7 is a right perspective exploded view thereof; and,

FIG. 8 is a front elevation exploded view thereof, wherein the back elevation exploded view is a mirror image of the front elevation exploded view, and wherein the top plan and bottom plan exploded views are identical to the front elevation exploded view.
